UNITED STATES PATENT OFFICE

PETER DOSCH, OF STRATFORD, CONNECTICUT, ASSIGNOR, BY MESNE ASSIGNMENTS, TO
ALEMITE CORPORATION, OF CHICAGO, ILLINOIS, A CORPORATION OF DELAWARE

OILING APPARATUS

Application filed November 21, 1918. Serial No. 339,692.

It is the purpose of my invention to supply an apparatus which, while adapted to use in connection with mechanism of many kinds, is especially adapted to the oiling of the moving parts of automobiles, motor boats and the like. Generally stated, my invention consists in a suitable reservoir or receptacle which shall be supplied, automatically or otherwise as desired, with oil, and an indicator easily accessible to the operator, whereby upon moving a pointer to appropriate points thereon, oil will be supplied at the desired time and in the desired quantity to the point designated on the indicator.

The apparatus herein illustrated and described disclose two forms of many in which my invention may be embodied. One of them simpler and less expensive than the other, will be described first.

Referring to the drawings Fig. 1 is a vertical sectional view, certain parts being shown in elevation, of a simple form of apparatus embodying my invention; Fig. 2 is a vertical sectional view taken on the line 2—2 of Fig. 1 and looking in the direction of the arrows; Fig. 3 is a plan view of the apparatus shown in Fig. 1; Fig. 4 is a plan view taken on the line 4—4 of Fig. 1; Fig. 5 is a vertical sectional view, certain of the parts being shown in elevation, of a more elaborate form of apparatus embodying my invention; Fig. 6 is a vertical sectional view of a part of that which is shown in Fig. 5, taken at right angles thereto; Fig. 7 is a plan view taken on the line 7—7 of Fig. 5; Fig. 8 is a plan view taken on the line 8—8 of Fig. 5; Fig. 9 is a plan view of the upper or index plate of Fig. 5; Fig. 10 is a horizontal sectional view taken through the several discharge ports of Fig. 5.

Referring first to Figs. 1 to 4, both inclusive, 1 represents a reservoir or tank, preferably of metal, provided with a filling plug 2. 3 is the cylinder of a pump within the tank provided with a piston 4, preferably having a cup leather 5 as its packing, which through connecting rod 6 and eccentric 7, is operated by a crank 8 on the outside of the reservoir. 9 is the inlet port for the pump which discharges through its open lower end 10. 11 is a shaft loosely journalled near its upper end in the top of the reservoir, as at 12, and at its lower end is a bearing 13 in the pump casting 14. 15 is a disk fast on the end of the shaft 11 and provided with a seating spring 16 and a series of holes 17, see Figs. 1 and 4, each of which registers with an appropriate tube 18, which extends to the part of the mechanism to be lubricated by it. It will be noted that the tubes 18 are so located that each registers with its proper opening 17 in the disk, but that they are not spaced in straight line as are the holes. This is so that there may be more space for the proper engagement of the tubes with the bottom of the pump casting 14 and also so that the tubes may extend therefrom to the parts they are respectively to lubricate more directly and conveniently than would otherwise be possible.

19, see Figs. 1 and 3, is a pointer on the upper end of the shaft 11 which co-acts with an indicator plate 20 on the upper side of the reservoir, which plate has a series of indicia 21 designating the parts—fan shaft, steering gear, etc.—to which the tubes 18 extend respectively.

The operation of the parts thus far described embodied in a simple form of apparatus is as follows:

Oil is put in the reservoir 1, wholly or partially filling it as desired. The pump is ordinarily submerged in the oil. At such time as the operator desires, which will depend upon the time that has elapsed since the last preceding oiling, the extent to which the mechanism has been in motion and the character of the work performed by it, the operator moves the pointer 19 in succession to such of the indicia 21 on the index plate 20 as designate the parts respectively he desires to lubricate, and as the pointer reaches the desired indicia in succession and comes to rest thereat, the operator turns the crank 8 such number of times as will generate the requisite pressure in the oil chamber below the pump to inject oil through the appropriate tube 18 to and upon the part to be lubricated. After lubrication of the desired parts the pointer will be returned to its primary or a neutral position midway between any two of the indicia, as shown in Fig. 3.

When the pointer is in this position the holes 17 in the disk 15 will likewise be at a neutral point, i. e., not in registration with the tubes 18, so that there will be no passage of oil through them and thus none to the parts in excess of the amount desired by the operator.

Referring now to Figs. 5 to 10, both inclusive, 22 represents the reservoir, 23 the shaft, 24 the pointer and 24^a the index plate provided with indicia 21. These parts are or may be substantially the same as above described. 25 is an oil inlet pipe which connects with the usual oil pump of the engine diagrammatically shown as a pump similar in construction and operation to that illustrated in Figures 1 and 2 and having its corresponding parts designated by similar reference characters. The pump is preferably driven from the engine crank shaft by gearing, although it may be hand operated as shown in Figures 1 and 2. At each reciprocation of the piston 4 oil is injected through the pipe 25 into a chamber 26, see Fig. 7, which is in effect a pump barrel or cylinder, because within it a piston 27 is located which at each injection of oil through the pipe 25 is pressed toward the opposite end of the chamber, compressing a spring 28 and uncovering an oil port 29 through which the oil enters the interior of the reservoir 22, and as the oil pump of the engine makes its back stroke, the action of the spring 28, causes the piston 27 to make its return movement into substantially the position shown in Fig. 7. The piston 27 is attached to a piston rod 30, which is pivoted at 31 to a link 32, which in turn is pivoted to a bellcrank lever 33, which is pivoted as at 34 to a fixed bracket 35. The lever has on its other end a pivoted pawl 36. 37 is what I term a pan valve, because it is made in the general form of a dish or pan, the walls 38 whereof extending upwardly, terminate in an annular upper edge upon which are located equally spaced series of equally spaced ratchet teeth, with which teeth the pawl 36 engages. Between each series of ratchet teeth is a smooth or toothless section 39 on the upper edge of the pan valve and in the wall of the pan valve at a suitable distance from its bottom, as shown best in Figs. 5 and 10, is an opening 40, and somewhat above it and likewise in the wall of the pan valve is a series of openings 41. As shown in Fig. 5, in the same horizontal plane as the opening 40 is a series of tubes 42, which lead, respectively, to the parts which are to be lubricated, one of such parts being illustrated as a bearing 42^a. The openings 41 are preferably equal in number and spacing with the tubes 42.

The openings 41 connect with a pipe 43 which leads back to the oil pump of the engine or to the reservoir therefor. In the center of the pan valve there is an upwardly presented boss 44, which acts as a bearing or

step for the lower end of the shaft 23 and upon the shaft is rigidly fastened an arm 45, which, during the movement of the pointer 24 and the consequent movement of the shaft 23, will be brought into contact with a pin or post 46 rigidly attached to the bottom of the pan valve.

The operation of the parts forming the apparatus last above described is more automatic than that of the simpler form of apparatus first described and is as follows:

When not in operation the pointer 24, the same as in the instance of the simpler apparatus, will be left on the indicator plate 24^a at a neutral point between two of the indicia, in which position the arm 45 on the shaft 23 will be resting against the pin 46. When the parts are in this position the oil pump of the engine will at each of its reciprocations inject oil through the pipe 25 which will actuate the piston 27, which through the train of connecting devices will in turn actuate the pawl 36; but inasmuch as at this time the pawl is on one of the smooth toothless sections of the upper edge of the pan valve, there will be nothing but an idle back and forth movement of it, and the oil injected into the pan valve will flow back again through that one of the openings 41 in the pan valve as is then in registration with the return pipe 43, to the engine pump or reservoir. In other words, the entire apparatus will be idle except for the stated flowing of oil into and out of the reservoir 22.

When, however, the operator desires to lubricate any part he will move the pointer 24 to that one of the indicia 21 as designates the part to be lubricated, and this movement of the pointer 24 will bring the arm 45 in contact with the pin 46 and rotate the pan valve in such manner that an opening 40 will be brought near a tube 42 which leads to the part to be lubricated and, at the same time, some of the teeth on the valve into active relationship to the pawl 36, so that oil will pass from the pan valve to such part until the pawl has made as many forward movements as will coincide with the number of ratchet teeth in the series with which it is then in registration, and when the pawl has reached the end of that particular series of teeth, it will pass upon the smooth adjoining surface 39 and there will then be no further rotation of the pan valve, but by that time the opening 40 therein will have passed away from the oiling tube 42 with which it has just been in registration and the further supply of oil thereto will cease, and it will be noted that because the openings 41 are preferably equal in number and spacing with the tubes 42, that by the time the operation of the pawl has carried the opening 40 out of registration with the oiling tube 42 with which it was in registration, that the back flow opening 41 which is next adjacent to the tube 42 through

which oil has just been supplied, will have moved into registration with the back flow pipe 43, so that the injected oil will thereupon flow back to the engine or its reservoir. Obviously instead of there being a series of openings 41 coinciding in number with the oiling tubes 42, a single back flow port 41 may be employed, but this will necessitate the return of the pan valve to primary position by hand at the termination of each lubricating operation. I prefer the construction shown and described, because if present the pulsations of the oil pump of the engine automatically perform all the requisite operations, thus avoiding necessity for watchfulness and care on the part of the operator.

The operator will thereupon move the pointer to such other of the indicia as designate the other parts which he desires to lubricate and the above described operation will then be repeated.

It will be obvious to those who are familiar with such matters that the two apparatus which I have herein described and illustrated are two forms only of many in which my invention may be embodied, and that the details of construction may be changed without departing from the essentials of the invention. As an example of such modification, instead of the valve plate 15 shown in Figs. 1 and 4 having a radial line of openings 17 therein, there may be a single opening as shown at 40 in Figs. 5 and 8. If so, the tubes 18 must be arranged upon a concentric circle, so that the single hole in the valve plate will engage with them during the rotation of the plate. I prefer, however, for the simpler apparatus, the construction shown in Figs. 1 and 4, because it will then be possible to provide additional oiling tubes 18, should the same be desired, and also it will be possible to have any two or more of the holes 17 register with the oil tubes connecting with two or more similar parts, as, for instance, with the four springs, or with the two king pins, and the like. I therefore do not limit myself to the details nor to the particular embodiments of the invention herein described and illustrated.

I claim:

1. A lubricating system for the bearings of a machine, comprising a pipe leading to a bearing, a source of lubricant under variable pressure a valve to control the flow of lubricant from said source into said pipe, hand-operated means to open said valve, and means, operated by the pressure of the lubricant, to close said valve.

2. A lubricating system for the bearings of a machine, comprising an oil reservoir, a conduit leading from the reservoir to a bearing, a valve to control the flow from the reservoir to the bearing, said valve being normally closed, mechanism operated by moving parts of the machine and arranged

to move the valve and normally out of engagement therewith, and manually controlled means to bring the valve and said mechanism into operative relation, said mechanism being arranged to move said valve to closed position at a predetermined time after the valve and mechanism are brought into cooperative relation. 70

3. A lubricating system for the bearings of a machine, comprising a feed pipe leading to a bearing, a lubricant supply pipe in which the lubricant therein is subjected to rapid increases and decreases of pressure, a valve between the feed pipe and the supply pipe, a reciprocable piston, a spring to oppose its motion in one direction, and means connected with said piston, to move said valve when the pressure in the lubricant supply moves the piston against the pressure of said spring. 75

4. In apparatus of the class stated an oil receptacle, means to automatically supply oil thereto, a movable valve having a plurality of discharge ports, a plurality of oil conveying ducts adapted to register with the ports in the valve, an index plate having indicia coinciding with the said ducts, means provided with a pointer adapted to co-act with the indica on the index plate whereby the valve may be successively rotated into and out of registration with the ducts, and means to automatically terminate the flow of oil. 80

5. In apparatus of the class stated an oil receptacle, means to automatically supply oil thereto, means to prevent flooding of the receptacle, a movable valve having a discharge port, a plurality of oil conveying ducts adapted to register successively with the discharge ports in the valve, and means to rotate the valve so that its discharge port may be successively brought into and out of registration with the said ducts. 95

6. In apparatus of the class stated an oil receptacle, means to automatically supply oil thereto, means to prevent flooding of the receptacle, a movable valve having a discharge port, a plurality of oil conveying ducts adapted to register successively with the discharge port in the valve, means to rotate the valve so that its discharge port may be successively brought into and out of registration with the ducts and the means to prevent flooding of the receptacle brought into operation. 110

7. In apparatus of the class stated an oil receptacle, means to automatically supply oil thereto, means to prevent flooding of the receptacle, a movable valve having a discharge port, a plurality of oil conveying ducts adapted to register successively with the discharge port in the valve, an index plate having indicia coinciding with the ducts, means provided with a pointer adapted to co-act with the indica on the index 120 130

plate whereby the valve may be rotated so that its discharge port may be successively brought into and out of registration with the ducts and the means to prevent flooding of the receptacle brought into operation.

8. A lubricating system comprising, in combination, a lubricant supply tank, a plurality of bearings to be lubricated from said tank, lubricant expelling means for forcing lubricant from said tank, a valve casing presenting a plurality of outlets, a plurality of tubes connecting said outlets and said bearings, a valve in said casing presenting a passage for conveying lubricant from said tank to one of said outlets and valve actuating means operable by reciprocation of said lubricant expelling means.

9. A lubricating system comprising, in combination, a lubricant supply tank, a plurality of bearings to be lubricated from said tank, lubricant expelling means for forcing lubricant from said tank, a valve casing presenting a plurality of outlets, a plurality of tubes connecting said outlets and said bearings, a valve in said casing presenting a passage for conveying lubricant from said tank to one of said outlets and valve actuating ratchet and pawl mechanism operable by reciprocation of said lubricant expelling means.

10. A lubricating system, comprising a lubricant supply reservoir, a plurality of bearings to be lubricated from said reservoir, lubricant expelling means for forcing lubricant from said reservoir, a valve casing presenting a plurality of outlets, a plurality of conduits connecting said outlets and said bearings, a valve in said casing presenting a passage for conveying lubricant from said reservoir to one of said outlets, and valve actuating intermittently engaging mechanism operable by reciprocation of said lubricant expelling means.

11. A lubricating system, comprising a source of lubricant, a plurality of bearings to be lubricated from said source, a valve casing presenting a plurality of outlets, lubricant expelling means for forcing lubricant from said source to said casing, a valve having a port adapted to register with the outlets in said casing, means to open said valve, and automatically operable means to close said valve.

12. A lubricating system, comprising a plurality of bearings to be lubricated, a source of lubricant, a valve casing connected to said source, a plurality of conduits connecting said casing to said bearings, a valve in said casing, means to open said valve to permit flow of lubricant from said casing to one of said conduits, and means operated by the flow of said lubricant to close said valve after a predetermined quantity of lubricant has been supplied to said conduit.

13. A lubricating system, comprising a source of lubricant, a distributing valve, a

reciprocating pump for forcing lubricant from said source to said valve, a plurality of bearings to be lubricated, conduits connecting said valve and said bearings, means for opening said valve, and means operable by the pressure impulses from said pump to close said valve.

14. A central lubricating system comprising a lubricant supply reservoir, a bearing to be lubricated, variable pressure pump means for forcing lubricant from said reservoir, a conduit connecting said means with said bearing, valve means in said conduit, said valve means being manually operable, and means automatically operated by a lubricant pressure impulse in said conduit to close said valve.

15. A central lubricating system comprising a lubricant supply reservoir, a bearing to be lubricated, a variable pressure pump for forcing lubricant from said reservoir, a conduit connecting said pump with said bearings, a manually operable valve in said conduit, and means automatically operated by lubricant pressure in said conduit to stop the flow of lubricant to said bearing.

16. A central lubricating system comprising a source of lubricant, a power operated pump fed from said source, a plurality of bearings to be lubricated, a pipe system connecting said bearings with said pump, and means for controlling the successive lubrication of said bearings, said means comprising manually operated mechanism for initiating the supply of lubricant to one of said bearings and means automatically operable by a lubricant pressure impulse for discontinuing the supply of lubricant to said bearing.

17. A central lubricating system comprising a source of lubricant, a power operated pump fed from said source, a plurality of bearings to be lubricated, a conduit system connecting the discharge of said pump with said bearings, valve means in said conduit, a single conduit leading from said valve means to said source, manually operable valve means controllable to permit flow of lubricant from said valve means to one of said bearings, and means operated by the lubricant supplied to said valve means to close said valve so that it will prevent flow of lubricant to the bearing and permit flow from said valve means through said second conduit to said source.

18. A central lubricating system comprising a source of lubricant, a pump fed thereby, a bearing to be lubricated, conduit means connecting said pump with said bearing, a valve intermediate said pump and bearing and normally preventing flow of lubricant to the bearing, a passage from said valve to said source, said passage normally permitting flow from said pump through said valve to said source, manually operable means for positioning said valve to permit flow of lubricant

to the bearing and prevent flow to said source, and automatic means to restore said valve to its normal position.

19. A central lubricating system comprising a source of lubricant, a pump fed thereby, a bearing to be lubricated, conduit means connecting said pump with said bearing, a valve intermediate said pump and bearing and normally preventing flow of lubricant to the bearing, a passage from said valve to said source, said passage normally permitting flow from said pump to said source, manually operable means for positioning said valve to permit flow of lubricant to the bearing, and lubricant operated means for restoring said valve.

20. A central lubricating system comprising a source of lubricant, a pump fed thereby, a bearing to be lubricated, conduit means connecting said pump with said bearing, a valve intermediate said pump and bearing and normally preventing flow of lubricant to the bearing, a passage from said valve to said source, said passage normally permitting flow from said pump to said source, manually operable means for positioning said valve to permit flow of lubricant to the bearing, and lubricant operated means for restoring said valve after a predetermined quantity of lubricant has been supplied to the bearing.

21. A central lubricating system comprising a source of lubricant, a pump fed therefrom, a bearing to be lubricated, conduit means connecting said pump and bearing, a valve in said conduit means, a return passage from said valve to said source, and means controlled by a lubricant pressure impulse in said conduit means to operate said valve to cut off the supply of lubricant to the bearing and to permit flow of lubricant to said source after a predetermined quantity of lubricant has been supplied to said bearing.

In testimony whereof I have signed my name to this specification.

PETER DOSCH.
